UNITED STATES PATENT OFFICE.

ASA ASHWORTH, OF SALAMANCA, NEW YORK.

VALVE-GRINDER.

1,158,021.

Specification of Letters Patent. Patented Oct. 26, 1915.

Application filed May 27, 1915. Serial No. 30,730.

To all whom it may concern:

Be it known that I, ASA ASHWORTH, a citizen of the United States, residing at Salamanca, in the county of Cattaraugus and State of New York, have invented certain new and useful Improvements in Valve-Grinders, of which the following, taken in connection with the accompanying drawings, is a specification.

10 The invention relates to valve grinders; and the improvement consists in providing valve grinding mechanism by means of which the valves can be rapidly reciprocally rotated with perfect freedom of movement, the spindle for turning the valve being so centered as to tension as to grind all parts of the valve and valve seat equally thereby making a perfect fit between the two parts in the shortest possible time.

20 A further object is to provide grinding spindles which while having a centering pressure on the valves are so loosely held and surrounded by the reciprocating mechanism as to constantly adapt themselves to 25 any inequality or inaccuracy in the valve and valve seat, thereby greatly aiding in the quick smooth grinding of the parts. It is experimentally found that manual reciprocation is nearly ideal for grinding valve 30 seats. This would of course be tedious and tiresome. The adaptability permitted in the loosely mounted spindles gives this ideal adjustment so that with light tension the valve and valve seat are ground to a perfect fit with the least amount of abrasion; and the invention consists in the novel features and combinations hereinafter set forth and claimed.

35 In the drawings, Figure 1 is a perspective view of the underside of the valve grinder showing the construction and arrangement of the parts; and Fig. 2 is a top plan view of the same. Fig. 3 is a sectional view at line X X in Fig. 2 showing an elevation 40 of the pinions and crank shaft for the reciprocation of the racks and pinions; and Fig. 4 is a perspective view of the driving mechanism for the racks and pinions, a portion of the frame being broken away to show 45 the cam on one end of the crank shaft and the attachment of the toothed rack thereto. Fig. 5 is a sectional view at line Y Y in Fig. 50 55 showing an elevation of one of the brackets for holding one of the spindles with the toothed racks slidably supported therein at

each side of the central pinion on the spindle and the means for giving tension to said spindle in holding the valve on its seat while grinding. Fig. 6 is a sectional view at line Z Z in Fig. 5 showing the spindle with the 60 pinion attached theron and loosely mounted between the toothed racks at each side, said racks being slidably supported with a loose fit in the supporting bracket. Fig. 7 is an enlarged perspective view of the end 65 of one of the spindles showing the centering punch in the middle of the flattened end of the spindle; and Fig. 8 is a plan view of the top of the valve with the groove therein showing the round opening in the center of 70 the groove to receive the centering punch on the spindle end.

Like numerals of reference refer to corresponding parts in the several views.

75 The numeral 10 designates the metal frame which supports the grinding mechanism. The frame 10 consists of a head portion 11 with a slotted hole 12 therethrough to receive the standard or shaft 13 therein for adjustably supporting the frame 10 on 80 the shaft 13, the head 11 being clamped on the shaft 13 at any desired height by means of a suitable bolt through lugs 14, the head being slotted or split at 15. The opposite side of the head has the groove 16 within 85 which the pinions 17 and 18 are revolvably mounted. The pinion 18 has the cams 19 on the opposite sides thereof to form the crank shaft, the cams 19 being surrounded by the rings 20 which have the arms 21 extending out therefrom for pivotal attachment to the ends of the toothed racks 22 at each side.

90 The frame 10 has the slotted portion 23 extending out from the head 11, the closed lengthwise slot 24 extending lengthwise of the central portion of said part 23 to receive therethrough the extension 25 on the brackets 26, a thumb-screw 27 with washer 28 being attached to the extension 25 to hold the 100 bracket 26 rigidly against the side of part 23 of the frame 10, the thumb-screw permitting the quick adjustment of the bracket 26 at any desired point along the slotted portion 23.

105 The bracket 26 has the opening 33 therein and the crosswise grooves 29 in the opposite sides thereof with suitable lugs each side of the grooves 29 to hold the racks 22 loosely and slidably in line for their reciprocative movement. In order to reciprocally 111

turn the valve a spindle 30 is provided in the bracket 26, being loosely mounted through a hole 31 in the lower portion of the bracket, a threaded opening 32 being provided through the upper portion of the bracket as formed by the central opening 33. A threaded nut 34 fits within the opening 32 and has the lock nut 35 thereon for holding it firmly in the adjusted position. The nut 34 has a central lengthwise hole to permit the spindle 30 to slide vertically therethrough.

A pinion 36 is attached to the spindle 30 within the opening 33 in the bracket 26 to mesh loosely in the racks 22 at each side and a tension coil spring 37 is provided between the upper end of the pinion 36 and the lower end of the nut 34 to give the desired pressure on the valve. The nut 34 is of sufficient length so that it may be turned into the threaded opening 32 to thereby give any desired tension to the spring 37 yet permitting the spindle 30 to be manually thrust upward so that the pinion 36 escapes above the racks 22 thereby permitting the free movement of the bracket 26 along said racks without removal of the spindle 30 and the pinion 36 attached thereto. The loose support of the pinion 36 in racks 22 and the spindle 30 in the bracket 26 permits said spindle to adjust itself to any movement or inequality in the grinding of the valve, a movement which is essential to the quick and perfect grinding of the surface of said valve.

In order to center the pressure of spindle 30 on the valve, a groove 38 is provided in the top 39 of the valve and has the enlargement 40 central of said groove 38 to receive the bit portion 41 of the spindle 30, which bit has the central point or punch 42 which fits in the opening 40 thereby invariably holding the bit 41 firmly in the centered position and automatically seeking said centered position when the spindle 30 and bit 41 descend into the groove 38. The central point 42 is slightly longer than the flattened wing portions of the bit 41 each side of said point so that the pressure of said bit 41 is always central of the valve top 39 since it bears in the enlargement 40. The wing or flat portions of the bit serve only to rotatively reciprocate the valve. Other means might be provided to reciprocate said valve without departing from my invention so long as the pressure of said bit is applied through the central portion thereof and not through the wing or extended portion thereof.

The driving gear 17 may be power driven but is preferably manually rotated by means of the crank 43 attached to the shaft 44 of the pinion 17 so that all that is necessary to grind the multiple valves of a multiple engine, as for automobiles and other uses, is to provide the number of brackets 26 on the

frame 10 corresponding to the number of valves to be ground, adjusting said brackets according to the exact relation of the valves to one another and supporting the frame 10 at the desired height above said valves. The spindles 30 are then manually inserted in the grooves 38, and a sufficient amount of abrasive is placed in the joint between the valve and the valve seat. The spindles 30 are then reciprocally rotated by turning the crank 43 thereby reciprocally moving the two racks 22 to accomplish said rotation of the spindles. In order to obtain the highest efficiency in grinding the valves the tension should be adjusted as lightly as possible to produce the abrading effect desired otherwise the periphery of the valve will be scored and roughened instead of smoothed and shaped to a perfect fit with the valve seat.

The light tension of the spindle 30 on the valve and the loose holding of said spindle in the racks 22 leave the valve free to seek a fit on the valve seat as it is continuously reciprocally rotated by said spindle and racks. In order to obtain this continuous drive of the spindles the two driving racks are necessary so that one may alternate the other without pause, the two cams 19 being shaped so that the alternate driving movement of the racks 22 is continuous.

I claim as new:

1. A valve grinder comprising a frame, brackets on said frame having openings in line with one another therein, a spindle rotatively mounted in each of said brackets, 100 elements movably contacting one each side of said spindle in said brackets, and means for the alternate movement of said elements to continuously rotatively reciprocate said spindles.

2. A valve grinder comprising a frame, brackets adjustably attached to said frame having openings in line with one another therein, a spindle revolvably mounted in holes through each of said brackets, a pinion on each of said spindles within said opening in each of said brackets, toothed racks slidably supported in said openings in said bracket one each side of said pinions to mesh therewith, and means for the alternate movement of said racks to continuously rotatively reciprocate said spindles.

3. A valve grinder comprising a frame having a slot therein, brackets adjustably attached to said frame at spaced distances 130 in said slot, said brackets having openings therein in line with one another, a spindle loosely mounted in each of said brackets to rotatively move the same, a pinion on each of said spindles within said opening in said bracket, toothed racks one each side of said pinion to loosely mesh therewith and slidably supported in the opposite walls of the openings in said brackets, pinions rotatively mounted on said frames, and cams one each 136

side of one of said pinions to alternately reciprocally move said racks and rotatively reciprocate said spindles.

4. A valve grinder comprising a frame, 5 brackets adjustably attached to said frame having openings therein, a spindle loosely and slidably mounted in holes through each of said brackets, a pinion on each of said spindles within said opening in said bracket, 10 toothed racks slidably supported in said brackets on each side of said pinions to loosely mesh therewith, an adjusting nut threaded in the hole for said spindle in the upper side of said frame having a hole 15 there-through to receive the upper end of said pinion, a coil tension spring between said adjusting nut and the top of said pinion on said spindle to thereby adjust the pressure of said spindle on the valve, said frame 20 having said opening therein sufficiently large above said pinion to raise said pinion free of said racks for the sidewise adjustment of said bracket and spindle, and cams and gearing revolvably mounted in said frame

to give an alternate continuous reciprocative motion to said racks and rotation to said spindles.

5. A valve grinder comprising a frame, spindles rotatively mounted on said frame, means to rotatively reciprocate said spindles, 30 a flat bit end on each of said spindles to engage a groove in the valve top to rotate the same, a pin central of said bit end having a rounded point extending beyond said flat bit end to engage a similarly shaped opening central of said valve top in said groove, said flat bit end supported by said pin a spaced distance above the bottom of said crosswise groove in said valve top to permit the adaptive leaning of said spindles in any 35 direction on said rounded point.

In testimony whereof I have affixed my signature in the presence of two witnesses.

ASA ASHWORTH.
